UNITED STATES PATENT OFFICE.

EDWARD R. INMAN, OF TIPTON, INDIANA.

CARBURETER.

SPECIFICATION forming part of Letters Patent No. 700,777, dated May 27, 1902.

Application filed April 19, 1899. Renewed October 2, 1901. Serial No. 77,316. (No model.)

To all whom it may concern:

Be it known that I, EDWARD R. INMAN, of Tipton, in the county of Tipton and State of Indiana, have invented new and useful Improvements in Carbureters; and I do hereby declare the following to be a full, clear, and exact description of said invention, reference being had to the accompanying drawing, and to the figures of reference marked thereon, which forms a part of this specification.

My invention relates to improvements in carbureters to be used in connection with gas-engines and will be fully understood by a reference to the accompanying drawing, in which the figure is a central vertical section.

The same figures of reference indicate identical parts throughout the drawing.

The object of my invention is to provide a carbureter by means of which the combusted exhaust products of a gas-engine are utilized for the purpose of heating the carbureting-chamber and the oil which is introduced therein for the purpose of forming gas and vapor.

I am aware that many forms of carbureters are in use which employ the exhaust of a gas-engine as the heating agent; but all of these, so far as I am aware, are intricate constructions, consisting of hot plates or a series of pipes which are difficult and expensive of construction and are objectionable in the fact that the plates or pipes aforesaid so occupy the carbureting-chamber that not enough space is left for gas, thus causing the ready supply of such gas to be meager and insufficient, and, further, that the air-passage through such pipes or plates is so circuitous that the efficiency of the gas-engine which is supplied by the carbureter is greatly reduced because of the impossibility of obtaining a sufficient charge through passages that are thus obstructed. To overcome all of these difficulties and objections is the object of my invention.

My device consists of a carbureting-chamber 1, located within a larger chamber, which is termed the "exhaust-chamber," 2. The walls 1' of the carbureting-chamber converge toward the bottom or downwardly, so that a conical chamber is formed with the smaller area at the bottom. Around the outside of

the walls 1' is formed an annular horizontal flange 3, and thus a dam 4 is formed by that portion of the wall 1' which extends above the flange 3.

Above the carbureting-chamber is placed a cover 5, which has at its lower edge a horizontal flange 5', which is coincident in diameter with flange 3, on which said flange 5' sits. The inner diameter of cover 5 is several inches larger than the outer diameter of dam 4, so that a trough 6 is formed between the outer face of dam 4 and the inner wall of cover 5. Trough 6 is the initial receptacle for oil as it enters the carbureting-chamber 65 through a pipe introduced at the port 17. As the trough becomes filled with oil said oil overflows dam 4 in a thin equal sheet, and thence down the converging walls of the carbureting-chamber 1 and is heated by the walls 70 1', which walls receive their heat from the combusted exhaust products of a gas-engine as they enter chamber 2 at the port 7, into which port 7 the exhaust-pipe of a gas-engine is introduced. By this construction the walls 75

alone of the carbureting-chamber are caused to heat the oil by direct contact therewith, and to thus perform the functions which, according to the best of my information and belief, have heretofore been accomplished by 80 a complicated series of plates or pipes of various forms and combinations. Hence the comparative simplicity of my device is obvious, a simple, free, and unobstructed carbureting-chamber being one of the valuable features 85 of my invention. As the exhaust enters port 7 it meets the pointed diverging conical bottom 8 of the carbureting-chamber, which point is located centrally over port 7. By this construction the exhaust is evenly deflected 90 about the chamber 1, and its walls 1' are thereby uniformly heated. As a further means of causing an equal distribution of the exhaust about the walls of the chamber

1 the escape-port 9 at the top of the exhaust-chamber 2 is of considerably greater circumference, but equal in its combined area, to the area of port 7, which necessitates the escape of the exhaust throughout the entire area of said escape-port 9 and further serves to cause 100 the exhaust to impinge closely about the exterior walls of the carbureting-chamber,

whereby the heat of the exhaust is utilized to the fullest extent. Port 9 communicates with an annular channel 10, extending entirely around the outside of chamber 2 and beneath trough 6, whereby heat is also applied to the bottom of said trough for the obvious purpose of heating the oil at this point. A port 11 is formed in the outer wall of channel 10 for the final exit of the exhaust.

10 In cover 5 are formed two ports 12 and 12', which serve as an inlet for free air and an outlet for carbureted air and either of which may serve the respective purposes specified.

15 From the bottom of the carbureting-chamber 1 a pipe 13 leads through the wall 2' of the exhaust-chamber, said pipe being the means whereby oil is withdrawn from the carbureting-chamber.

20 For the purpose of heating the carbureting-chamber preparatory to starting an engine gasoline may be poured into the bottom of the exhaust-chamber 2 through the opening 14, provided for this purpose, then ignited and permitted to burn, when the walls of the 25 carbureting-chamber 1 will become sufficiently hot to generate gas when oil is introduced into said chamber.

20 The outer wall of channel 10 is provided at its upper edge with an outwardly-projecting 30 annular flange 15, which flange is equal in diameter to flange 3 of the carbureting-chamber and also to flange 5' of the cover, said flanges respectively forming the means whereby the various portions or elements of 35 my device are secured together by the bolts 16.

When my device is attached to a gas-engine for operation, the inlet air or gas port to the cylinder of said engine is put in communication with the carbureting-chamber by 40 means of a suitable pipe leading into port 12 or 12', and as air is drawn through the chamber 1 a sufficient amount of vapor is mingled with it to produce an explosive mixture and suitable operating medium for a gas-engine.

45 It should be understood that the oil to be used with my device should be of a volatile nature and preferably crude petroleum fresh from the well and of at least 38° gravity. Such oil is introduced to the receiving and 50 distributing trough 6 through the pipe at 17, and as said trough becomes filled the oil flows over the dam 4 in a thin and equal sheet and down the converging walls 1' of the generating-chamber, which oil thus becomes heated and vaporized, and the vapor 55 rises into the cover 5 (the space in the cover being understood as being included, practically, as a portion of the generating-chamber) and there mingles with the air as it passes 60 through the ports 12 and 12'.

It will be readily seen that by the construction herein shown and described a carbureting-chamber may be formed of ample capacity, efficient in operation, and the passage of air through the same is easy and unobstructed. My device also serves as an effectual muffler to the noise of the exhaust of

a gas-engine, the escape-port 9 at the top of the exhaust-chamber being the main feature which conduces to this end in that it causes 70 a dissipation or separation of the body of the exhaust in such a manner that the final escape of said exhaust into the atmosphere is comparatively gradual or prolonged over what it would be were it permitted an unobstructed escape, and, further, the exhaust being compelled to escape through the whole area of the escape-port 9 (by reason of the area of said escape-port being equal to the area of port 7, aforesaid, by way of which the exhaust enters said chamber) that portion of the exhaust which makes its exit through port 9 at or nearest the point of location of port 11 escapes earliest to the atmosphere, while that portion of the exhaust which makes its 85 exit through port 9 at the farthest point from port 11 escapes latest to the atmosphere. It is therefore evident that the exhaust is so dissipated as to be deprived of its force and detonation as it escapes to the atmosphere. 90

Having thus described my device, what I claim as new, and desire to secure by Letters Patent, is—

1. In a carbureter for gas-engines, an open, unobstructed carbureting-chamber with 95 downwardly-converging walls, air-ports leading to and from said carbureting-chamber, a receiving and distributing trough located at or near the top of the converging walls of said carbureting-chamber, means of introducing oil to and withdrawing same from said carbureting-chamber, an exhaust-chamber of larger diameter than, and receiving said carbureting-chamber, an annular escape-port at the top of said exhaust-chamber, an annular channel formed about the top of said exhaust-chamber, into which said escape-port leads, a port in the outer wall of said channel, means of admitting the combusted, exhaust products of a gas-engine to said exhaust-chamber, means of generating preliminary heat in the exhaust-chamber, about the walls of the generating-chamber; all constructed, combined and operating substantially as shown and described. 115

2. In a carbureter for gas-engines, a carbureting-chamber with downwardly-converging walls, an oil receiving and distributing trough located at the top of said carbureting-chamber, a cover superimposed above said carbureting-chamber, ports in said cover, adapted for the passage of air therethrough, an exhaust-chamber adapted to receive and envelop said carbureting-chamber, a port leading to said exhaust-chamber, a passage leading from said exhaust-chamber of greater circumference than and of the same area as said inlet-port, all constructed and combined substantially as shown and described. 120

3. In a carbureter for gas-engines, the combination of an exhaust-chamber, an inlet-port leading to said chamber, an escape-port leading from said chamber, an annular channel formed about said exhaust-chamber with 130

which said escape-port communicates, a port
communicating from said annular channel to
the atmosphere; all so combined, located and
proportioned as to deaden or muffle the sound
of the exhaust of the gas-engine to which said
carbureter is attached, substantially as shown
and described.

In testimony whereof I affix my signature
in presence of two witnesses.

EDWARD R. INMAN.
